UNITED STATES PATENT OFFICE.

WILLIAM HOFACKER, OF NORWOOD, PENNSYLVANIA.

DESIGN FOR AN ESKIMO DOLL.

48,111.

Specification for Design.

Patented Nov. 9, 1915.

Application filed September 7, 1915. Serial No. 49,395. Term of patent 7 years.

To all whom it may concern:

Be it known that I, WILLIAM HOFACKER, a citizen of the United States, residing at Norwood, in the county of Delaware and State of Pennsylvania, have invented a new, original, and ornamental Design for Eskimo Dolls, of which the following is a specification, reference being had to the accompanying drawing, forming a part thereof.

Figure 1 is a front view of an Eskimo

doll, showing my new design, and Fig. 2 is a back view.

I claim:

The ornamental design for an Eskimo doll, as shown.

WILLIAM HOFACKER.
